PAPER-FEED CONTROL FOR CALCULATING-MACHINES.

1,293,245.

Specification of Letters Patent.

Patented Feb. 4, 1919.

Original application filed May 20, 1916, Serial No. 98,853. Divided and this application filed March 27, 1918. Serial No. 224,958.

To all whom it may concern:

Be it known that I, OTTO THIEME, a citizen of the United States, residing at the city of St. Louis, State of Missouri, have invented a certain new and useful Improvement in Paper-Feed Controls for Calculating-Machines, of which the following is a full, clear, and exact description, such as will enable others skilled in the art to which it appertains to make and use the same, reference being had to the accompanying drawings, forming part of this specification, in which—

Figure 1 is a top plan view of a combined adding and typewriting machine on which my improved paper feed control is employed.

Fig. 2 is a vertical sectional view through the rear end of said machine.

Fig. 3 is a horizontal sectional view through the rear end of said machine.

Fig. 4 is a detail view of the parts connected with my improved paper feed control.

Fig. 5 is a side elevational view of the parts shown in Fig. 4.

Fig. 6 is a side elevational view of certain of the parts shown in Fig. 4.

Fig. 7 is a side elevational view of the ratchet and pawl mechanism.

This invention relates to a new and useful improvement in paper feed controlling mechanism for calculating machines, and is a division of an application filed by me May 20, 1916, Serial Number 98,853.

The calculating machine disclosed in the parent case is of the combined adding and typewriting machine class commercially known as the Moon-Hopkins billing machine, the particular type of Moon-Hopkins

billing machine disclosed in said parent application being characterized by a tally roll printing mechanism on the tally strip of which a duplicate record is kept of the items and totals thereof printed on the sheet of

paper carried by the paper carriage located at the upper forward portion of the machine and on the sheet of paper carried by which is also received printing impressions from the words-printing mechanism of the type writer.

In the parent case, there is disclosed an auxiliary paper carriage supporting the tally strip which may be manually or automatically tabulated to position said strip to

receive printing impressions from the tally roll type in different columns. There is also means for returning the paper carriage of the tally roll mechanism to its home or starting position. This present application relates to the means for feeding the tally strip and controlling the feed thereof so that line-spacing of the tally strip only occurs when necessary or desired.

In the drawings, 1 indicates the digit keys of the adding mechanism, and 2 the result keys thereof. 3 is the motor key for effecting an operation of the adding mechanism. 4 are the keys of the typewriting mechanism. 5 is the laterally movable paper carriage identified with the typewriting mechanism and on the sheet of paper carried by which are also made impressions from type carried by the type-carriers 100, as set forth in the parent case. 6 is the platen of the laterally movable carriage before referred to. 119 and 268 are the register wheels.

500 is the casing or housing which incloses the rear portion of the adding mechanism, said housing or casing having brackets 501 extending rearwardly therefrom, in which brackets is arranged a grooved shaft 502. 503 are the side frame pieces of the tally roll paper carriage from which is suspended a frame 512 carrying the roll 516 containing the tally strip. This tally strip is fed upwardly over an idle roller 514 and between pressure rollers 508 and 509, then between suitable paper guides 506 and under platen 505. A serrated plate 504 is secured to the upper cross bar of the frame 503 on the edge of which the tally strip may be severed. Means are disclosed in the parent case for tabulating the frame 503 so as to laterally adjust the tally strip opposite the printing type on the segments 561, such tabulation occurring after said printing segments have been positioned by the racks 100. When positioned, the type are caused to make an impression by vibrating the frame 503, causing the platen 505 to press the paper against the type in the printing line. 562 indicates the inking ribbon which is normally located over the type in the printing line.

The controlling mechanism for the paper feed identified with the tally strip, is shown in the accompanying drawings as being coupled-up with the mechanism for causing a

printing impression of the platen 505, but it is obvious that the paper feed controlling mechanism may be separated therefrom. The laterally movable paper carriage 5 carries a notched bar 39 on which are adjustably mounted blocks 578 supporting pivoted stops 579. These stops coöperate with an arrow head 577^a on the forward end of a bar 577 having a slot and pin connection with a frame part of the machine, as shown in Figs. 4 and 6, whereby when the carriage 5 is moved laterally, these stop blocks 579 will successively pass the arrow head 577^a and, by engaging the anticlinal portions thereof, force the bar 577 rearwardly. If this lateral movement is incident to tabulation, the blocks 579 are so positioned on the bar 39 that at the end of each tabulation movement, they will lie in front of the head 577^a and in this manner hold the bar 577 rearwardly while the paper carriage 5 is stationary.

The rear end of bar 577 is connected to a rock arm 576, on the inner end of sleeve 574 mounted on the shaft 575, finding bearing 25 in the frame parts of the machine. The upper end of sleeve 574 carries an arm 573 to which is connected a bar 572 having a slot and pin connection with the side framing of the machine whereby the rear end of said 30 bar may be guided in its movement. The rear end of bar 572 is bifurcated and normally engages the upper end of a lever 570 carrying the pin 570^a at its upper end. This pin is normally held forward by means of 35 springs 570^b. The lower end of bar 570 is connected to a moving part of the adding mechanism, not shown herein, but which causes the bar 570 to be operated at each 40 operation of the adding mechanism, *i. e.*, the bar 570 is first caused to be lowered and then to be raised. If the bar 577 stands in its forward position during this operation of the adding mechanism, the vibration of bar 570 will be idle; but if one of the 45 stops 579 holds the bar 577 rearwardly, pin 570^a on the upper end of bar 570 will be caused to engage in slot 568^a in the forward end of lever 568 mounted on shaft 502, and consequently, said lever 568 will be operated, 50 *i. e.*, rocked, first downwardly, then upwardly. Lever 568 is provided with an adjustable stop 569 on its outer end which engages track plate 520 and in this way the limit of the upward movement of lever 55 568 may be adjusted.

581 indicates a guard plate normally held upwardly by means of a spring 583, and which guard plate is provided with a guard finger 582 at its inner end. This guard 60 plate is loosely mounted on the shaft 502 and projects inwardly through the opening C in the casing alongside of the lever 568. The upward movement of guard plate 581 is limited by a stop shoulder C' in the upper 65 wall of the slot. Hence in the normal posi-

tion of the parts, the guard finger is held below the slot, as shown in Fig. 5, so that pin 570^a is free to move into and out of the slot, depending upon the position of the bar 577.

70 Plate 568 is fixed to the shaft 502 and when the pin 570^a lies in the slot, as shown in Fig. 5, the adding mechanism is operated, and bar 570 will be depressed, which movement causes the plate 568 to be likewise depressed, rocking the shaft 502. As the bar 570 moves downward, its pin 570^a will pass behind guard finger 582 and eventually engage the guard plate 581 and cause it to move in unison with plate 568. When pin 80 570^a is thus located behind the guard finger, the guard finger closes the slot 568^a and prevents the withdrawal of pin 570^a. On the upward movement of bar 570, the plate 568 and the guard plate 581 will rise together 85 until the guard plate is arrested by the shouldered stop C'. The continued upward movement of the plate 568 will locate the slot 568^a above the guard finger, as shown in Fig. 5, and the slot being thus exposed, the 90 pin 570^a may be disengaged from the plate 568, which will occur when stop 579 on the paper carriage is moved out of engagement with the arrow head 577^a.

95 Plate 568 carries a post 568^b which passes through a slot in the guard plate 581. This post is fixed to the plate 568 and carries a fixed arm 584 at its outer end, which fixed arm is provided with a pin or lateral projection 585. This pin coöperates with a bell 100 crank lever 593 mounted on the end of a shaft 594 (see Fig. 5) which shaft, by its rocking movement, effects the feeding of the inking ribbon (not claimed herein).

105 When the plate or rock arm 568 is depressed to rock the shaft 502, the platen carried by the frame 503, is brought into contact with the type in the printing line, but the pressure necessary for effecting the printing impression is not exerted upon said 110 platen until the lost motion between the plate 511 and slot in the shaft 502 is taken up. When this lost motion has been overcome, the final pressure is placed upon the platen, this occurring at the last operation 115 of the downward movement of the rock arm 568.

120 When the rock arm or plate 568 is lifted, it is immaterial whether the frame 503 is first restored to its normal position or whether the lost motion of the plate in the groove is first taken up. The normally retracted position of the frame is determined by means disclosed in the parent application, and when the frame 503 is 125 arrested in its retracted position, the shaft 502 continues to be rocked, thereby absorbing the lost motion referred to until the stop member 569 engages the track plate 520. This continued rocking movement of the 130

shaft 502 is utilized in line-spacing the tally strip.

One end of the paper feed roll 509 (the right-hand end, as viewed from the front 5 of the machine, see Fig. 1) is provided with a hand-wheel 586 for manual operation. The opposite end of said feed roll is provided with a ratchet wheel 587, (see also Fig. 7). This ratchet wheel co-operates with 10 a spring-pressed centering pin 588 carried by an arm pivotally connected to the frame 503, which centering pin permits the manual rotation of the feed roller 509 in either direction.

15 To mechanically effect the line-spacing of the paper, I mount a plate 589 (see Fig. 7) on the shaft 502, said plate having a slot and pin connection with the frame 503, so as to permit independent movement thereof, and 20 said plate also having a projection which fits into the groove of shaft 502, but not tightly, permitting a slight independent play of said plate. Plate 589 carries a paper feeding pawl 590 which is normally held in 25 operative position by a spring 591. A bar 592 (Figs. 1 and 3) is mounted in a bearing provided by one of the brackets 501, said bar being adjustably held in position by means of a set screw 593. This bar is cut away at 30 intervals, as at 592^a, so that whenever said bar is adjusted to locate one of its cut-away portions opposite, or in line with, the paper-feeding pawl 590, (see Fig. 7) said paper-feeding pawl is permitted to engage the 35 ratchet wheel and line-space the tally strip. When, however, the paper-feeding pawl 590 rides upon the bar, as shown by dotted lines in Fig. 7, the vibration of the pawl 590 will be idle. Thus, after a printing impression, 40 and after the frame 503 has been retracted the full measure of its retractive movement, the continued rocking of the shaft 502 in taking up lost-motion therebetween and said frame, will rock the plate 589 and vibrate 45 the paper-feeding pawl 590. If the bar 592 is so adjusted as to have a recess in line with said paper-feeding pawl, then the paper-feeding pawl will engage, and by operating the ratchet wheel, line-space the tally 50 strip; but, if said paper-feeding pawl is riding the bar, its vibration will be idle.

The bar 592 is sufficiently long (see Figs. 1 and 3) to hold the paper-feeding pawl 590 in a disabled position throughout the entire 55 travel of the tally-roll carriage, except when it occupies that position which may be designated as the extreme left position, when, by the presence of the recess 592^a, line-spacing will be effected. The bar 592 may have 60 a second recess 592^b cut on its opposite side, as shown in Fig. 3, so that by rotating the bar 592, line-spacing of the tally strip can be effected at a point before the carriage reaches its extreme left position. Of course, 65 in using the recess 592^b for effecting the line-

spacing feed of the tally strip at this point, the blocks should be adjusted accordingly, such as the carriage return block, etc., so as to properly articulate and harmonize the various devices which are controlled by the 70 typewriter carriage.

The casing or housing 500 incloses the adding mechanism and the printing type of the tally-roll printing mechanism, and carries on its outside the laterally movable 75 platen carriage with its platen 505 for making a printing impression from said tally-roll type. The levers 568, guard plate 581, and the ribbon feed operating arm 584 project through the slot C in the casing 500, but 80 as above described, have detachable connection with their operating parts, i. e., the bar 570 and its connections. Hence, when the casing is removed, the adding machine may be operated as usual, and though the type 85 segments 561 are positioned, no printing impression can be taken therefrom, nor will the paper-feeding mechanism be operated.

What I claim is:

1. In an apparatus of the character described, the combination of a laterally movable paper carriage, paper feed rolls, a ratchet on one of said rolls, a paper feeding pawl co-operating with said ratchet, means for operating said paper feeding pawl, said 90 means including a detachable connection, and a second paper carriage provided with means for rendering said detachable connection effective or ineffective, both of said 95 paper carriages having platens upon which 100 printing impressions are made by separate sets of printing type.

2. In an apparatus of the character described, the combination of a laterally movable paper carriage, paper feeding rolls, a 105 ratchet and pawl mechanism for driving said rolls, means for operating said paper feeding ratchet mechanism, said means including a detachable connection, a second paper carriage, and adjustable blocks on said 110 second paper carriage for rendering said detachable connection effective or ineffective whereby the paper feed in the first mentioned carriage may be controlled, both of 115 said paper carriages having platens upon which printing impressions are made by separate sets of printing type.

3. In an apparatus of the character described, the combination of a vibratable frame carrying a platen, paper feeding rolls 120 mounted in said frame, means for vibrating said frame, said means including a detachable connection, and means controlled by said detachable connection for operating said paper feeding rolls or permitting them 125 to remain idle.

4. In an apparatus of the character described, the combination of a laterally movable paper carriage, paper feed rolls, a ratchet on one of said rolls, a paper-feeding 130

pawl coöperating with said ratchet, and an adjustable notched bar coöperating with said pawl to permit or prevent engagement between said pawl and said ratchet, depending upon the position of said laterally movable carriage.

5. In an apparatus of the character described, the combination of a laterally movable paper carriage, means for rocking said carriage, paper feeding rolls mounted in said carriage, a ratchet on one of said rolls, a

pawl designed to coöperate with said ratchet, said pawl being operated by the same means which rocks the carriage, and a notched bar which is adjustable both rotatably and longitudinally whereby the ratchet may be operated to feed the paper only in certain positions of the carriage. 15

In testimony whereof I hereunto affix my signature this 21st day of March, 1918.

OTTO THIEME.
